FURNACE

John V. Boland and Bradley Burton, St. Louis,
Mo.; said Burton assignor to said Boland

Application June 1, 1942, Serial No. 445,302

1 Claim. (Cl. 110—78)

This invention relates to furnaces; and has special reference to the prevention of the formation of clinkers along the walls of the firebox, and to the promotion of combustion.

In coal burning furnaces, irrespective of the types of grates that are used, it is common experience that clinkers are formed along and in connection with the side walls within the firebox of the furnace. These clinkers along the side walls of the firebox reduce and restrict the area immediately above the grates and prevent burning of the coal throughout the full width of the grate. It is necessary to remove these clinkers from time to time by the use of slice bars or other implements, and such repeated removal eventually breaks the faces of the firebrick, initiates deterioration of the firebrick, and requires frequent and costly repairs.

Objects of the present invention are to provide an apparatus or equipment for use in coal burning furnaces using different types of grates that will substantially prevent, or largely reduce, the formation of clinkers on and along the side walls of the furnaces, thereby avoiding the necessity of removing clinkers by the use of slice bars or other implements that break the faces of the firebrick and initiate deterioration, requiring shut-down of the furnaces and expensive repairs; to provide means for use in furnaces of certain types that will substantially prevent or greatly reduce damage to the clinker chill plates mounted in the furnace walls along the sides of the grates; and to provide means for tempering the coal in a manner to promote combustion thereof, and also to prevent burning of metal furnace parts now subject to rapid deterioration and damage by combustion of the coal in the furnace.

Another object of the invention is to provide an apparatus including pipes arranged in the furnace and having discharge ports for steam admitted into or forced through said pipes, so that the steam will be discharged in jets along and against the side walls of the furnace to prevent the formation of clinkers and substantially promote combustion of the coal, and also dispense with the use of slice bars and the like for the removal of clinkers, thus preventing damage to the firebrick and other parts of the furnace.

Another object of the invention is to provide a steam pipe having ports for discharging steam therefrom into the coal adjacent to metallic parts of the furnace that are usually damaged as a result of combustion, thereby preventing such damage, promoting more perfect combustion of

the coal, and generally prolonging the life of the furnace structure, and particularly the metallic parts that are usually damaged by combustion.

Other objects will be apparent from the following description, reference being made to the annexed drawing, in which—

Fig. 1 is a front elevation of a furnace equipped with the present invention.

Fig. 2 is a vertical sectional view transversely of the lower portion of the furnace, showing the invention embodied in a furnace having a grate of the chain type.

Fig. 3 is an enlarged fragmentary sectional view, similar to Fig. 2, but showing more clearly the arrangement of the steam injection pipe relative to the chain grate.

The present invention is contained in a furnace having a movable grate 11 of the chain type mounted in a combustion chamber formed by walls 2 composed of firebrick. Cast iron plates 12 extend along the sides and across the rear of the combustion chamber slightly above but approximately in the plane of the upper side of the grate 11 and at the under side of a ledge 13 extending continuously along the sides and rear of the combustion chamber. This provides spaces 14 along the two sides and along the rear of the combustion chamber in which the pipe 15 is mounted. The spaces 14 are obtained by spacing the lower portions of the two side walls below the plates 12 a greater distance apart than the upper portions of said side walls, and forming longitudinal inwardly extending ledges at the unions of said lower and upper portions of said walls. The metallic plates 12 that are embedded in said side walls extend inwardly beyond the inner surfaces of said lower portions of said side walls and cover the lower sides of said ledges.

The pipe 15 is located below the plane of the upper surface of the grate 11, below the ledge 13 and the inwardly extended portion of the plates 12, and above the shaft 16 which extends through one of the side walls 2 and is rotative to operate the grate 11 in the usual manner. The pipe 15 leaves the space below the grate 11 wholly unobstructed, and is formed with a longitudinal series of holes 17 through the upper side thereof. Said holes are preferably of uniform size, about one-fourth inch in diameter, and spaced apart about two inches from center to center. The two side portions or stretches of the pipe 15 extend through the front wall 8 of the furnace and have communication with a source of steam supply, either exhaust steam or live steam, as desired, through pipe connections 9 equipped with

valves 10 to regulate the amount of steam passing to said pipe 15, and to permit or prevent the passage of steam to said pipe as desired. The steam may be generated in a boiler heated by the furnace. The steam jets ejected through the series of holes 17 pass upwardly between the inner edges of the plates 12 and the adjacent sides of the grate 11 into coal extending laterally from the upper surface of said grate across said spaces 14 to the plates 12 and to the side walls 2 above the ledges 13. Said steam tempers the coal along the sides of the combustion chamber, thereby promoting combustion of said coal and substantially preventing or largely reducing the formation of clinkers on and along the side walls of the combustion chamber. This avoids the necessity of removing clinkers by use of slice bars or other implements that break the faces of the firebrick and cause deterioration of the furnace structure.

The location of the pipe 15 wholly within the space 14 and in a position leaving the space below the grate 11 wholly unobstructed, provides several advantages. It leaves the grate freely operative and movable without interference by said pipe. The grate may be removed and replaced and repaired more conveniently than if the pipe extended into the space below the grate or into the space between the upper and lower portions of the grate. The pipe may be removed and replaced without interference by the grate and without difficulty in extending the pipe into the space within or below the grate. The holes in the upper side of the pipe are at all times accessible regardless of the grate when the furnace does not contain fuel or the remnants of fuel after combustion.

From the foregoing, it is apparent that this invention attains all of its intended objectives and purposes efficiently, economically and satisfactorily. The invention may be added in fur-

naces already constructed, or included in furnaces during their initial construction and as a part of the permanent equipment thereof. The arrangement of the invention may be varied 5 within the scope of equivalent limits without departure from the nature and principle of the invention as defined by the appended claim.

We claim:

- 10 In a furnace having a rear wall, a front wall, and two side walls composed of firebrick co-operating with said rear and front walls to form a combustion chamber, said two side walls having lower portions spaced apart a greater distance than the upper portions thereof and having longitudinal inwardly extended ledges at the unions of said lower and upper portions of said side walls; metallic plates embedded in said side walls and extending inwardly beyond the inner surfaces of said lower portions of said side walls 15 and forming the under sides of said ledges, a movable chain type grate mounted in said chamber between said lower portions of said side walls and having its upper surface approximately in the same plane with said plates and having its 20 two longitudinal sides separated from said lower portions of said side walls by intervening spaces, a shaft for operating said grate, and steam pipes extending along and within said spaces between the sides of said grate and said 25 30 lower portions of said side walls above said shaft and under said ledges and below the plane of the upper surface of said grate and having longitudinal series of holes in their upper sides for discharging steam upwardly between the inner edges of said plates and the adjacent sides of said grate into coal extending laterally from the upper surface of said grate across said spaces to said plates and said side walls above said ledges.
